HAT CROWN POUNCING MACHINE
CONSTRUCTIONBurling D. Wells, Danbury, Conn., assignor to The
Mallory Hat Company, Danbury, Conn., a cor-
poration of Connecticut

Application May 7, 1943, Serial No. 485,987

5 Claims. (Cl. 223—20)

This invention relates to apparatus for operating upon fur felt hat bodies and more particularly to an apparatus for pouncing the crowns of hat bodies.

One of the objects of this invention is to provide an improved crown pouncing apparatus that will be capable of achieving reliable and more efficient relative traverse between the rotating hat crown and the operating tool and that will do so with simple, positive and inexpensive mechanism. Another object is to provide in a hat-working machine an improved mechanism for effecting and controlling the relative traverse between the hat crown and the operating tool and, more particularly, where the tool is of substantial dimension, such as a pouncing pad, to provide for the dependable control of the orientation of the tool relative to all of the successive portions of the hat crown which it is to engage during relative traverse between it and the crown.

Another object is to improve the construction, operation and performance of hat-working machines, such as crown pouncing machines, of the type in which the operating tool, such as a pouncing pad, is traversed from the band portion of the hat, then the side, then the square and finally to the tip of the hat, or vice versa, during rotation of the hat crown about its own axis. More particularly, another object is to provide, in apparatus of the just-mentioned character, a simplified and dependable mechanism for effecting traverse of the tool and for positively orienting the tool for proper engagement with whatever portion of the hat crown that it happens to engage in the course of its traverse.

Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings, in which is shown one of the various possible embodiments of my invention,

Figure 1 is a front elevation of the apparatus;
Figure 2 is a plan view;

Figure 3 is a side elevation as seen from the right in Figure 1, certain parts being shown in central vertical section and certain other parts being indicated diagrammatically.

Similar reference characters refer to similar parts throughout the several views of the drawings.

As conducive to a clearer understanding of certain features of my invention, it may at this point be noted that crown pouncing machines as heretofore produced and made available, such as the type of pouncing machine described in Cassé, U. S. Patent No. 2,006,260, issued June 25, 1935, in which the oval-cross-sectioned hat crown is rotated about a horizontal axis and in which the pouncing tool, by itself of any suitable character or driven in any suitable way, is traversed from the band portion of the hat to the tip, or vice versa, by causing its entire mounting to be swung about a vertical axis, various difficulties in construction, operation and performance are encountered and among these a principal difficulty or objection is the manner in which contact relationship between the pouncing pad and the hat body are attempted to be effected or maintained throughout the varying conditions met with throughout the path of traverse of the tool.

The hat crown can have various peculiarities of shape; thus its side portions are not always necessarily parallel to the axis and more frequently (though oval in cross-section) are frusto-conical. These merge into the top of the hat in a region called the "square" which is usually a curve, but the radius of curvature is widely variable. Sometimes it is of small radius and sometimes it is of large radius. The top of the hat, called the "tip," likewise is not necessarily always flat or plane, but can be outwardly convex and this can be further complicated by the fact that the top is not circular in area, but is usually oval.

The fact that the hat crown is oval can be counteracted or compensated for by any suitable or known form of mechanism which acts, during the rotation of the hat block to which the hat crown is snugly fitted to shift the actual axis of the hat crown so that the portions of the crown along the line or path of traverse of the tool and which are thus presented to the tool to be operated upon are always at the same radial distance from the actual axis of rotation of the hat body, and by such means also substantial uniformity of pressure of engagement of the tools against the hat crown can be maintained during the operation. Also various expedients may be employed to achieve substantial uniformity of surface speed of rotary movement of the hat crown.

In spite of such compensating factors, the various expedients heretofore employed in the endeavor to maintain flatness or tangency of engagement of the traversing pouncing tool with all portions of the hat crown with which it moves

into engagement during its traverse, still do not result in uniformity of action or in dependability and uniformity of engagement and the detrimental character of these and the above-mentioned difficulties can be judged when it is considered that the pouncing tool is an abrasive tool and frequently operates at high velocity and, therefore, can cut relatively deeply and fast if its operative area is not oriented properly to the peculiar shape of the hat crown.

Various expedients have heretofore been attempted to achieve such orientation. In the above-mentioned Cassé patent, a complicated train of driving mechanism is provided in the endeavor to maintain orientation of the tool relative to the hat body, but the path which it enforces upon the traversing pad is essentially in the form of a square with curved corners and curvilinear convex sides as shown in Figure 2 of the patent, whereas the shape of the hat crown is essentially that of a frustum of a cone with a rounded top and oblate, with the result that, particularly in the band portions of the hat crown, that is, where the crown joins the brim, the pad has one vertical edge portion thereof forced against the hat body with greater pressure than other portions of the pad. Other expedients have included spring action with or without a floating type of mounting for the pad in the effort to obtain some degree of self-orientation.

One of the dominant aims of this invention is to avoid such deficiencies, complications and shortcomings as here inherent in prior expedients and to provide dependability and positiveness of both actuation of relative traversing movement and orientation of the pad or tool throughout the varying conditions, angularities, curvatures and other shapes met with during the relative traversing movement between tool and hat crown.

Referring first to Figure 3, the apparatus may comprise a box-like base 10 having upstanding therefrom at one end a hollow standard 11 in the upper end of which is supported for rotation about a generally horizontal axis a chuck 12, controllable as by handles 13, for releasably engaging and supporting a hat block 14 upon which the crown of the hat body is snugly fitted. Any suitable means, not shown, may be employed to rotate the chuck and hat block at the desired relatively low rate of speed.

Where the hat crown and hence the hat block are oval in cross-section, the mounting and driving mechanism for the chuck 12 may comprise any suitable mechanism like that earlier above mentioned for shifting the actual axis of the oval hat block during its rotary movement and, if desired, also for varying the rate of drive during each revolution to achieve substantial constancy of surface speed of the portions of the oval hat body with which the tool engages during its traverse.

Any such mounting and driving means for the chuck 12 is conveniently mounted and housed within the upper end of the standard 11 and since it is well known it is not described or shown in detail and, by way of illustration, it may comprise mechanism of the kind or type disclosed in the above-mentioned Cassé patent.

Still referring to Figure 3, the tool may take any convenient or suitable form and, illustratively, may comprise a suitable backing or frame-like support 16 of suitable area having secured thereto, in any suitable way, a suitably resilient

or cushion-like element 17, made of a material like relatively soft rubber for example, and over the face of the element 17 extends a sheet 18 of suitable pouncing material, such as the usual or well known fine grade of sandpaper. For convenience of reference, the tool is designated by the reference character P and will hereafter be so referred to.

The hat body 20 mounted upon the block 14, 10 illustratively oval as appears from Figure 1, may have a brim B and for convenience of reference its crown C has a side portion E which merges into the tip T by way of the square S. With the tool suitably actuated or driven and the hat body 20 slowly rotated, a relative traversing movement between tool P and crown C is to be effected and insofar as the features of my invention are concerned such relative traverse may be effected in any suitable way, preferably by effecting movement of translation of the tool P relative to the crown C, and in any case, it is desired that the relative traverse be such that the tool operates successively upon side portion E, square S and tip T, either in that order or reversed or in a cycle comprising several strokes 25 of successive traversing movement; for example, the traversing movement may start at the portion E, adjacent the brim B, proceed over the square S to the center of the tip T, then reverse 30 through the square S and cover the side E to the brim B.

In the illustrative embodiment, the tool P and the chuck 12 are mounted and related to each other to provide an axis at right angles to the 35 axis of rotation of the chuck and preferably intersecting that axis and about which this relative traversing movement may take place. Thus, in the top plate 10^a of the base portion 10, I provide an aperture 22 of suitable size into which is 40 set a cylindrical casing 23 having a cylindrical side wall 24 flanged as at 25 to rest upon the top wall 10^a of the base 10 and by which it is rigidly secured to the base 10 in any suitable way as by screws or bolts not shown. The upper and 45 inside faces of the cylindrical wall 24 are machined to provide a bearing for a circular carrier plate 27 having a depending annular flange 28 that fits into the upper end of the cylindrical wall 24, thus giving the carrier plate 27 a good mounting for rotary movement about a vertical axis, somewhat in the manner of a turntable. Any 50 suitable means may be used to hold the carrier 27 rotatably assembled to the casing 23, such as a stud bolt 29 suitably shouldered and provided 55 with a nut 29^a at its lower end to mount it securely in the bottom wall 23^a of the casing 23 and suitably shouldered and provided with a nut 29^b at its other end to permit the carrier 27 to 60 rotate about the stud bolt 29 whose axis of course is coincident with the center of the carrier 27.

The axis of rotatable carrier 27, indicated at Y, is vertical and intersects the horizontal axis X of the chuck 12 preferably at a point substantially midway between the tip T and the brim B of the hat body and upon the carrier 27 there is provided a mounting and drive for the tool P so constructed that the tool P may pivot about a vertical axis radially displaced from the axis of rotary carrier 27.

70 A convenient form of such mounting and drive may comprise a frame 30 having a suitable base 31 that rests upon the carrier 27 and pivots, as later described, about a vertical axis radially displaced from the axis of carrier 27. Upstanding 75 from the base 31 are two spaced arms 33-34 in

the ends of which are suitable bearings aligned along a horizontal axis to receive trunnions 35 and 36, respectively, of a tool carrier frame generally indicated by the reference character 37.

Tool carrier frame 37 comprises a lower housing portion 37^a to the right-hand end of which, as seen in Figure 3, is secured the frame of an electric motor 38 whose horizontal shaft extends into the housing portion 37^a where it is provided with, or drives, a crank or eccentric indicated at 39 that is connected with a preferably lightweight or tubular rod 40 that extends upwardly through an upward hollow extension 37^b of the housing and that carries at its end the tool P.

With the motor 38 driven at a suitable speed, preferably relatively high, the tool P is thus rapidly reciprocated and by providing a universally mounted sliding bearing 41 in the upper end of the housing part 37^b for the drive rod 40, the pad P, during its general reciprocation and for each complete cycle, is given a movement in a closed curved path. Details of this drive and mounting for the pad P may follow the construction described in the above-mentioned Cassé patent.

The tool P is biased clockwise in Figure 3 and hence toward and against the rotating hat body by any suitable means, preferably by the unbalance brought about principally by the location of the motor 38 with respect to the horizontal axis of the trunnions 35-36 and variation or change in the pressure with which the tool P is pressed against the hat crown may be effected in any suitable way as, for example, by a shiftable counterweight 43 slidably carried on a rod 44 projecting from the housing 37 to the other side of the horizontal axis of trunnions 35-36.

Any suitable means may be employed to connect the frame 30 to the carrier 27 so that it may pivot about a vertical axis radially displaced from the vertical axis of rotation of carrier 27 and, by way of illustration, carrier 27 may have projecting upwardly from it and rigidly secured to it, as by a force fit, a stud bolt 48 that extends through a suitable hole 31^a in the base 31 of frame 30, a suitable washer and nut 49 threaded onto a lesser-diametered end portion of the stud 48 serving to hold the frame 31 and carrier 27 assembled while permitting freedom of pivoting of the frame 30 relative to the carrier 27. Stud 48 thus forms the vertical axis, indicated at Z, of pivoting for the tool P and this axis is in substantial alignment with the central vertical axis of the casing part 37^b and hence is substantially in the plane of the operative face of the pad P when the latter assumes a substantially vertical position relative to the horizontal axis of the trunnions 35-36. The radial displacement of the vertical axis Z of the stud 48 from the vertical axis Y of the carrier 27 is on the order of about the horizontal distance from the axis Y of carrier 27 to the tip T of the hat body held on the block in the chuck 12, these relationships being, generally stated, on the order of those shown in the drawings.

To the frame 30 is secured a horizontally-projecting arm 50, as by screws 51 that anchor the arm 50 to the base 31 of the frame 30, and in its outer end the arm carries a roller 52 rotatably secured thereto by a stud bolt 53, as is better shown in Figure 1. Roller 52 projects downwardly from arm 50 and into the cam slot 54 (Figure 2) of a horizontal cam plate 55 that is secured to the base 10 of the apparatus as by a screw 56 and a bracket 57.

The general relationship of the cam slot 54

and of the arm 50 to the several axes X, Y and Z above described is substantially like that better shown in Figure 2 in which the tool P is shown engaging the side portion E of the crown C adjacent the brim B, being at substantially the beginning of its two-stroke cycle of movement. At this point, the positive relationship mechanically between the parts insures that the frame 30 is so positioned about axis Z that the relatively flat face of the tool P, while tangent to the frusto-conical surface of the hat body, engages the latter in coincidence with the geometrical element the rotation of which generates the side E of the hat body and thus insures that the expansion of the tool P, during its reciprocation or its movement in a closed path, engages the hat body with uniform pressure throughout.

This is the point at which the tool P is brought into engagement with the hat body or is disengaged therefrom, at the respective start and stopping of the operation, as by corresponding control of the tool carrier frame 37, manually or otherwise, about the horizontal axis of the trunnions 35-36.

Beginning at that point, carrier 27 rotates clockwise as viewed in Figure 2, by any suitable drive an illustration of which is set forth hereinafter, and rotating slowly about its axis Y, the frame 30 with the tool carrier frame 37 partakes of motion of translation in clockwise direction along an arc indicated at R in Figure 2. This arcuate path of travel is in general such as to move the tool P from the side E of the crown C, over the square S, and to the tip T, and as this movement takes place, cam following roller 52 traverses along the cam slot 54 and by the shape of the latter causes the frame 30 and hence the tool P to pivot about axis Z in a manner always to keep the operative face of the tool P flat against or tangent to, as the case might be, the just-mentioned successive portions of the hat crown. This takes place to the accompaniment of actual motion of translation of the axis Z along the arc R and hence the cam slot 54 has the somewhat peculiar shape indicated in Figure 2, being of considerable length as compared to the axial length of the hat crown which the tool P itself traverses.

By the time tool P reaches the tip T of the crown, at which position, shown in Figures 1 and 3, the plane of its operative face is substantially at right angles to the axis X of the hat body, the tool carrier frame has been moved along the arc R by an amount on the order of 90°, and cam roller 52 is at the upper left-hand end of cam slot 54 (Figure 2), thus fixing the swinging of the tool P about axis Z so that its operative face is at substantially 90° to the hat crown axis X.

It will be noted that in this clockwise movement of translation along the arc R of the tool carrier frames and hence of the tool P, the positive cam control of the angle of the plane of the tool P to the crown axis of rotation X takes place with ease and certainty, the arm 50 that carries the cam roller 52 being disposed at an angle to the plane of the tool P such that the cam roller 50 is in effect pulled along the cam slot 54, the long leverage of the arm 50 making for greater ease of shift of the tool carrier frames about the axis Z.

When the carrier 27 is reversed in its rotary movement, thus to traverse the tool P from the tip T over the square S and over the side E up to the brim B, the camming action is reversed, the cam roller 52 being pushed in advance of

the tool carrier frames (instead of trailing, as during the first stroke), and this action takes place with nicety, smoothness and positiveness, the long leverage insuring ease of shift of the parts about the axis Z and hence ease of following movement of the cam roller 52 in the cam slot 54.

Reaching the end of this reverse stroke, the pad P again finds itself properly and uniformly aligned with and engaging the side of the crown and hence removal of the tool P from the hat body takes place without detrimental action.

With such cam control, any simple and suitable form of drive for the rotary carrier 27 to swing it slowly about its vertical axis may be employed, and here I may use simple gearing. Thus, for example, I may provide the inner face of cylindrical wall 24 of the casing 23 with teeth to form an internal gear 59 with which meshes a spur gear 60 rotatably carried by the stud 48 that is fixedly secured in depending relation to the carrier 27 as above described. Meshing with gear 60 is a gear 61 which is mounted co-axially with the internal gear 59 and the carrier 27, conveniently upon the above-mentioned stud-like bolt 29 which holds carrier 27 rotatably assembled to the casing 23.

Gear 61 is, in turn, driven by a gear 62 provided with suitable driving connections to a main drive shaft 63 accommodated within the hollow standard 11 and provided with suitable start and stop and reversing mechanism and controls therefore, the details of which can take any suitable form such as described in the Cassé patent and hence these are diagrammatically indicated at 64.

Accordingly, with main drive shaft 63 driven and controlled as just described, the carrier 27 is given rotary movement about axis Y through just about 90° to move frame 30 along arc R and to an extent to traverse the pad P from the tip T to the brim B or from the brim B to the tip T, the controls being preferably such that, as above indicated, the tool P is given two strokes of movement, namely, from the brim B, over the side portion E, the square S, the tip T (that being one stroke) and then from the tip T over the square S and over the side portion E to the brim B (this being the other stroke and being preferably a reversal of the first one).

If desired, speed-varying mechanism may be included in this drive to vary the rate of motion of translation along the arc R of Figure 2 and hence to alter the rate of tool traverse relative to the hat crown C according to the portions of the crown that are engaged by the tool P. Thus it may be desirable to speed up the traversing movement of the tool P during its passage over the square S. Such speed-varying mechanism may take any suitable form and may, for example, be interposed between the main drive shaft 63 (Figure 3) and the gear 62 and it may take the form of mechanisms so interposed in this drive in the above-mentioned Cassé patent.

Thus main drive shaft 63 may have a driving gear 65 to drive a gear 66 rotatably mounted upon a member 67 secured to the casing 23, member 67 forming a bearing for a shaft 68 to which gear 62 is secured. As shown in Figure 3, member 67 is shaped or conformed so that the axes of gear 66 and of shaft 68 are eccentric, the speed variation being achieved by a pin, roller, or stud 70 carried by the gear 66 and riding in a slot 11 of an arm 72 secured to the shaft 68 with the gear 66 driven at a uniform speed, the speed of drive of shaft 68 and hence of gear 62

becomes non-uniform and varied because the eccentric relationship of the parts effects change in angular velocity of shaft 68 as the radial distance of the pin or stud 70 changes during each revolution relative to the axis of shaft 68. The other gears are proportioned so that the swing of carrier 27 about its axis Y to give the tool P one stroke of traversing movement corresponds to a single revolution of the gear 66.

Other features of control, such as change in speed of reciprocating drive of the pad P, change in the pressure of the pad P against the hat body, and the like, may also be embodied in the apparatus and the corresponding mechanism may take forms such as those described in the Cassé patent.

Referring again to Figure 2, it may be noted that the cam plate 55 with its cam slot 54 can suffice for a substantial range of change of sizes and general configuration or shapes of hat crown C to be operated upon by the apparatus, the capacity of the tool P to pivot about the horizontal axis of the trunnions 35-36 giving it wide adaptability of self-accommodation or adjustment in directions toward or away from the hat crown at any point in its stroke of traversing movement. Risk of marring or damaging the hat body, present in heretofore known constructions as above noted, is minimized and for that matter, no matter at which point in the stroke of the relative traverse between tool and hat body that the two are separated or brought together, disengagement and engagement always finds the angular relationship between the face of the tool P and the axis of rotation of the crown C dependably determined so that cutting of the hat body by an edge of the tool is guarded against.

It will thus be seen that there has been provided in this invention an apparatus in which the various objects above mentioned together with many thoroughly practical advantages are successfully achieved.

As many possible embodiments may be made of the mechanical features of the above invention and as the art herein described might be varied in various parts, all without departing from the scope of the invention, it is to be understood that all matter hereinabove set forth, or shown in the accompanying drawings, is to be interpreted as illustrative and not in a limiting sense.

I claim:

1. A crown pouncing machine comprising means for rotatably supporting a hat body for rotation about a horizontal axis, a pouncing tool having an operative face of substantial area for engagement with the crown of the hat body, a rotatable carrier having means mounting it for rotary movement about a vertical axis, a frame having means for supporting said tool and for biasing it toward and against the crown of the hat body, means mounting said frame on said carrier for pivotal movement relative thereto about a vertical axis displaced from the axis of said carrier, cam and cam follower means for pivoting said frame and hence said tool about said second vertical axis and operating in response to rotary movement of said carrier about said first vertical axis to change the plane of the tool as the latter traverses the side, square, and tip of the crown, and driving means for said carrier to effect motion of translation of said frame and to effect coaction between said cam and cam follower means.

2. An apparatus as claimed in claim 1 in which said cam and cam follower means comprises a relatively fixed cam plate having a cam groove of

substantial length as compared with the length of the actual path of traverse of said tool relative to the hat crown, and an arm extending from said frame and carrying the cam follower, said follower riding in said cam groove.

3. An apparatus as claimed in claim 1 in which the driving means for said carrier is reversible to effect traversing movement of the tool relative to the hat crown in successive strokes with a reversal of direction of movement at the end of each stroke, said cam and cam follower means comprising a relatively fixed cam having a cam groove that is relatively long compared to the length of the traverse stroke of the tool, said frame having an arm of substantial length and supporting the cam follower at its end at a point such that a vertical plane extending through the cam follower and the midpoint of the face of the pad makes an acute angle with the pad face.

4. An apparatus as claimed in claim 1 in which said cam and cam follower means comprises a relatively stationary cam, and means mounting the cam follower onto said frame at a point such that a vertical plane passing through the cam follower and said second vertical axis makes an acute angle with the plane of the face of the tool.

5. In an apparatus for operating upon the crown of a hat body, the combination which comprises a mounting for rotating and supporting

the hat body, a tool presenting a substantially flat operative face for operating upon the crown and having a mounting therefor and means for biasing it against and toward the crown of the hat body, and means for effecting relative traversing movement between the tool and the rotating hat body so that the tool operates upon the side, the square, and the tip of the crown, said means comprising a carrier for one of said mountings, said carrier having means supporting it to swing about an axis at right angles to the axis of the hat crown, means pivotally supporting said one mounting upon said carrier to swing about an axis parallel to said carrier axis, means for driving said carrier in successively reversed rotary strokes to effect relative traverse from the brim over the square to the tip of the crown or vice versa, and cam and cam follower means responsive to the motion of translation of said one mounting caused by the rotary strokes of said carrier and operating throughout the range of said motion of translation to shift said one mounting about the axis of its support upon said carrier and thereby change the angle between the face of said tool and the axis of said hat crown, said cam having a configuration that is a function of the shape of said crown and a function of the spacing between said two parallel axes.

BURLING D. WELLS.
